UNITED STATES PATENT OFFICE.

WASYL SHULL, OF PALMERTON, PENNSYLVANIA.

TRUNK.

1,408,400.

Specification of Letters Patent. Patented Feb. 28, 1922.

Application filed April 7, 1921. Serial No. 459,333.

To all whom it may concern:

Be it known that I, WASYL SHULL, a citizen of Ukraine, residing at Palmerton, in the county of Carbon and State of Pennsylvania, have invented certain new and useful Improvements in Trunks, of which the following is a specification.

This invention relates to certain new and useful improvements in trunks and has particular reference to a trunk divided into a plurality of independent compartments with the compartments accessible by independently operable lock controlled doors.

One of the objects of the invention resides in the provision of a trunk or double walled construction with a heat insulating material placed between the walls so that papers or other articles may be placed within the compartments of the trunk without any damage resulting thereto.

A further object of the invention embodies a trunk containing a plurality of separate compartments with separate locking means for each compartment, the locking means for one compartment only being accessible upon the operation of the locking means for one of the other compartments.

With the above and other objects in view, the invention consists in the novel form, combination and arrangement of parts hereinafter more fully described and shown in the accompanying drawings, in which like reference characters indicate corresponding parts throughout the several views.

In the drawings,

Figure 1 is a perspective view of a trunk constructed in accordance with the present invention,

Figure 2 is a horizontal sectional view taken on line II—II of Figure 1, the same being partially broken away; a double walled construction with the insulation therebetween and the separate sections of one of the trunk compartments,

Figure 3 is a vertical longitudinal sectional view taken on line III—III of Figure 1 showing the main compartment of the trunk with the upper and lower sections thereof, and

Figure 4 is a cross sectional view taken on line IV—IV of Figure 1 showing the three compartments of the trunk with the locking means for two of the compartments.

Referring more in detail to the accompanying drawings, there is illustrated a trunk divided into a plurality of independ-

ent compartments with individual locking mechanisms for each compartment, the trunk embodying a base section 1 and a top section 2 hinged together at 3, as shown in Figure 4 with the top and bottom sections being of double wall construction with an insulating packing 4 interposed between the walls to protect the interior of the trunk from the effects of heat, cold, moisture, etc.

The lower front wall of the trunk bottom has the space between the double wall construction provided with transverse partitions 5 to divide the same into a central compartment 6 and lateral compartments 7. A door 8 is hinged as at 9 to the lower edge of the front wall as shown in Figures 1 and 4, the same being provided with a handle 10 and a permutation lock 11 engaging the upper horizontal partition wall 12 for the compartments 6 and 7.

The forward edge 2' of the cover section 2 of the trunk is spaced inwardly of the front wall of the base section as illustrated in Figure 4 to accommodate a double walled door 13 hinged as at 14 to the partition wall 12 while the upper end and sides of the door 13 carry a rearwardly directed flange 15 overlying the forward edge of the top section 2. The locking means for the door 13 includes hasps 16 hinged as at 17 to the opposite ends of the door 13, each hasp carrying an inwardly directed apertured lug 18 entering a slot 19 in the end wall of the cover section 2 with the apertured lug engaged by a bolt on the permutation lock 20, a lock 20 being provided at each end of the cover for association with the adjacent hasp and cover by a horizontal guard plate 21 as shown in Figure 1. The front wall of the base section 1 is constructed to provide a receptacle compartment 13' extending longitudinally of the trunk and closed by the door 13.

To lock the cover section 2 in closed position as shown in Figure 4, latch keepers depend from the lower edge of the forward end 2' and are engaged by permutation lock devices 22 supported on the front wall of the base section 1, the cover and base section 105 operating to form a relatively large main compartment 23. For transporting the trunk, the base section 1 is provided with belt handles 24.

In the use of the trunk, access to the compartments 6 and 7 is obtained by releasing the permutation lock 11 to permit the door

8 to move on the hinges 9, while access to the compartment 13' is obtained by releasing the hinged hasps 17 retained by the permutation locks 20, the locks 20 being accessible by moving the guard plates 21 on their pivotal mountings upon the cover section 2. It is necessary to open the door 13 to gain access to the permutation locks 22 for releasing the cover section 2 thereby exposing 10 the main trunk compartment 23. It will be noted that each of the compartments 6, 7, 13' and 23 are independently lock controlled and by the provision of permutation locks, different combinations may be provided for operating each door section. In view of the various shapes of the compartments, papers or articles of various characters such as jewelry and clothing may be placed within the trunk and securely locked 15 therein as well as protected by the double wall construction with the insulating packing material.

While there is herein shown and described, the preferred embodiment of the invention, 25 it is nevertheless to be understood that minor changes may be made therein without departing from the spirit and scope of the same as claimed.

What is claimed as new is:

30 1. A trunk of the type described comprising a base section, a cover section hinged thereto, said sections being of double wall construction, an insulating packing between the walls thereof, compartments formed in the front wall of the base section, a lock controlled door controlling access thereto, a hinged door carried by the base section, said base section having a compartment positioned above the first named compartments 35 accessible by opening the last named door and locking devices for the cover section positioned inwardly of the last named door.

40 2. A trunk of the type described comprising a base section, a cover section hinged thereto, said sections being of double wall construction, an insulating packing between the walls thereof, compartments formed in the front wall of the base section, a lock controlled door controlling access thereto, a hinged door carried by the base section, said 45

base section having a compartment positioned above the first named compartments accessible by opening the last named door and locking devices for the cover section positioned inwardly of the last named door, the locking devices for the second named door including swinging hasps carried thereby and permutation locks carried by the cover section cooperating therewith.

55 3. A trunk of the type described comprising a base section, a cover section hinged thereto, said sections being of double wall construction, an insulating packing between the walls thereof, the front wall of the base section being divided into upper and lower compartments, independently operating lock controlled doors for the upper and lower compartments and locking devices for the cover confined by the upper door.

60 4. A trunk of the type described comprising a base section, a cover section hinged thereto, said sections being of double wall construction, an insulating packing between the walls thereof, the front wall of the base section being divided into upper and lower compartments, independently operating lock controlled doors for the upper and lower compartments and locking devices for the cover confined by the upper door, said upper door being of double wall construction, the 70 front side of the cover section terminating inwardly of the front wall of the base section and a flange carried by the upper door overlying the adjacent edges of the cover section.

75 5. A trunk of the type described comprising a base section, a cover section hinged thereto, said base section having a plurality of compartments formed in the front wall thereof, independent lock controlled doors for each compartment and locking means for the cover section accessible upon opening one of the door sections.

80 In testimony whereof I affix my signature in presence of two witnesses.

WASYL SHULL.
